US0D1051808S

(12) **United States Design Patent** (10) **Patent No.:** **US D1,051,808 S**
(45) **Date of Patent:** **** Nov. 19, 2024**

(54) **PART OF A VEHICLE**

(71) Applicant: **FERRARI S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **35/516,856**

(22) Filed: **Apr. 5, 2022**

(80) **Hague Agreement Data**

Int. Filing Date: **Apr. 5, 2022**

Int. Reg. No.: **DM/220086**

Int. Reg. Date: **Apr. 5, 2022**

Int. Reg. Pub. Date: **Apr. 7, 2023**

(30) **Foreign Application Priority Data**

Oct. 6, 2021 (WO) WIPO109202

(51) **LOC (14) Cl.** **12-16**

(52) **U.S. Cl.**

USPC **D12/196**

(58) **Field of Classification Search**

USPC D12/86, 90, 92, 164; D21/433, 434, 533,
D21/535

CPC B62D 25/00; B62D 25/06; B62D 33/00;
B62D 35/00

See application file for complete search history.
